(57) **CLAIM**

We claim the ornamental design for an arrangement of fastening devices for a boot, as shown and described.

DESCRIPTION

FIGS. 1 through 6 represent a first embodiment of an

arrangement of fastening devices for a boot, showing our new design, whereby:

FIG. 1 is a top plan view of the first embodiment of an arrangement of fastening devices for a boot, showing our new design;

FIG. 2 is a rear elevation view thereof;

FIG. 3 is a right side elevation view thereof;

FIG. 4 is a front elevation view thereof;

FIG. 5 is a left side elevation view thereof; and

FIG. 6 is a bottom plan view thereof.

FIGS. 7 through 12 represent a second embodiment of an arrangement of fastening devices for a boot, showing our new design, whereby:

FIG. 7 is a top plan view of the second embodiment of an arrangement of fastening devices for a boot, showing our new design;

FIG. 8 is a rear elevation view thereof;

FIG. 9 is a right side elevation view thereof;

FIG. 10 is a front elevation view thereof;

FIG. 11 is a left side elevation view thereof; and

FIG. 12 is a bottom plan view thereof.

FIGS. 13 through 18 represent a third embodiment of an arrangement of fastening devices for a boot, showing our new design, whereby:

FIG. 13 is a top plan view of the third embodiment of an arrangement of fastening devices for a boot, showing our new design;

FIG. 14 is a rear elevation view thereof;

FIG. 15 is a right side elevation view thereof;

FIG. 16 is a front elevation view thereof;

FIG. 17 is a left side elevation view thereof; and

FIG. 18 is a bottom plan view thereof.

FIGS. 19 through 24 represent a fourth embodiment of an arrangement of fastening devices for a boot, showing our new design, whereby:

FIG. 19 is a top plan view of the fourth embodiment of an arrangement of fastening devices for a boot, showing our new design;

FIG. 20 is a rear elevation view thereof;

FIG. 21 is a right side elevation view thereof;

FIG. 22 is a front elevation view thereof;

FIG. 23 is a left side elevation view thereof; and,
